UNITED STATES PATENT OFFICE

156,330

CARRIER FOR CAPSULES AND THE LIKE

Mack R. Fields, Chicago, Ill., assignor to Abbott Laboratories, North Chicago, Ill., a corporation of Illinois

Application May 22, 1947, Serial No. 139,208

Term of patent 3½ years

(Cl. D16—2)

To all whom it may concern:

Be it known that I, Mack R. Fields, a citizen of the United States, residing in Chicago, in the county of Cook and State of Illinois, have invented a new, original, and ornamental Design for a Carrier for Capsules and the like, of which the following is a specification, reference being had to the accompanying drawings, forming a part thereof.

Fig. 1 is a perspective view of a carrier for capsules and the like, showing my new design; and

Fig. 2 is an end elevation showing the new design.

The opposite side and end of my carrier are the same as those shown.

I claim:

The ornamental design for a carrier for capsules and the like, substantially as shown and described.

MACK R. FIELDS.
